UNITED STATES PATENT OFFICE

138,647

DESIGN FOR A COMBINED WEATHER VANE AND FIGURE

Frank J. Dubke, Detroit, Mich.

Application January 6, 1944, Serial No. 112,186

Term of patent 7 years

(Cl. D52—1)

To all whom it may concern:

Be it known that I, Frank J. Dubke, a citizen of the United States, residing at Detroit, in the county of Wayne and State of Michigan, have invented a new, original, and ornamental Design for Combined Weather Vane and Figure, of which the following is a specification, reference being had to the accompanying drawing, forming part thereof, wherein:

Fig. 1 is a front view of a combined weather vane and figure showing my new design.

Fig. 2 is a side view of the same.

I claim:

The ornamental design for a combined weather vane and figure, as shown.

FRANK J. DUBKE.
